(57) **CLAIM**

The ornamental design for a drawer for washing machine, as shown and described.

DESCRIPTION

FIG. 1 is a top, front, perspective view of a drawer for washing machine showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a top, front, perspective view thereof, shown in a closed position.

The broken line showing of details in FIGS. 1 and 6 is included for the purpose of showing environmental portions of the drawer for washing machine that form no part of the claimed design.
